US00D554688S

(12) **United States Design Patent** (10) **Patent No.:** **US D554,688 S**
Elmore (45) **Date of Patent:** **** Nov. 6, 2007**

- (54) **SUNGLASSES**
(75) Inventor: **Eric G. Elmore**, Noblesville, IN (US)
(73) Assignee: **Fatheadz, Inc.**, Carmel, IN (US)
(**) Term: **14 Years**
(21) Appl. No.: **29/242,037**
(22) Filed: **Nov. 4, 2005**
(51) **LOC (8) Cl.** **16-06**
(52) **U.S. Cl.** **D16/326**
(58) **Field of Classification Search** D16/300-330,
D16/101, 332-338; D29/109-110; D24/110.2;
351/41, 44, 51-52, 62, 158, 92, 103-111,
351/156, 61, 114-119, 121-123; 2/426-432,
2/447-449, 441, 434-437

See application file for complete search history.
